GEORGE P. FINDLAY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE FRAME FOR AXMINSTER LOOMS

Application filed February 26, 1929. Serial No. 342,732.

The invention relates to improvements in tube frames for Axminster looms and it is the general object of the invention to provide a tube frame having a flexible hanger latch 5 which is readily detachable from the tube frame but normally held securely in position by its own resilience.

Axminster looms are ordinarily provided with a pair of spaced transporting chains 10 between which extend a plurality of tube frames. The latter are provided with hooks which engage the chains and as each tube frame approaches the position where it is taken from the chain and moved toward the 15 fabric these hooks are disengaged from the chains. The hooks occasionally break or for other reasons become unusable and it is desirable to be able to effect a ready replacement under such circumstances.

20 Tube frames of wide Axminster looms are ordinarily made of a hollow rectangular tubular bar and it is a further object of my present invention to provide a hook latch resilient either throughout its entire length or 25 at the lower portion thereof, the lower portion extending into the tubular bar and being held into engagement with some element rigid with the bar so that under normal conditions the latch by reason of its own resilience is maintained in operative relation 30 with respect to the tube frame.

It is a still further object of my present invention so to form the bracket on the tube frame and the hook latch that the latter may 35 readily be removed by means of a simple tool such for instance as a screw driver without moving the head or bracket from the tube frame.

With these and other objects in view which 40 will appear as the description proceeds, my invention resides in the combination and arrangement of parts hereinafter described and set forth in the claims.

In the accompanying drawings, wherein a 45 convenient embodiment of my invention is set forth,

Fig. 1 is a vertical section through the clutch and bracket of a tube frame for the usual Axminster loom, parts being shown in 50 elevation,

Fig. 2 is a view taken in the direction of arrow 2 looking at the end of the tube frame, the clutch being removed,

Fig. 3 is a view similar to a portion of Fig. 1 but illustrating the manner in which the 55 latch may be removed from the bracket, and

Fig. 4 is a detailed horizontal section on line 4—4 of Fig. 1.

Referring particularly to Figs. 1 and 2 I have provided the tube frame 10 formed substantially of a rectangular tubular bar to one side of which may be attached the yarn or tuft tubes 11. The head or bracket 12 has upper and lower parallel horizontal arms 13 and 14, respectively, which project into and are secured to the bar 10 by means of screws 15. A spool bearing 16 extends from the bracket and affords support for the spool S while a chain engaging tongue 17 extends to the right as shown in Fig. 1 of the spool bearing and projects between the links 18 of the transporting chain.

The clutch designated generally at C is provided with a lifting lip 19 adapted to engage the under portion either of the tube frame or the bracket to support the tube frame when the latter is disconnected from the chain. A stud 20 adjustably mounted in the upper end of the clutch is of usual construction and forms the means by which the tube frame is disconnected from the chain. A spring plunger 21 may be provided to cooperate with the stop motion which is effective to arrest movement of the loom should the tube frame fail to move to tuft forming position at the proper time. The matter thus far described is of common construction employed more particularly on the ordinary form of so-called wide Axminster loom and forms no part of my present invention.

In carrying my present invention into effect I provide an improved form of connection between the bracket and the chain in the form of a spring hook or latch 30 the upper end of which is bent back on itself to form an overhanging hook 31 which may engage one of the links 18 as shown in full lines in Fig. 1 when the tube frame is connected to the transporting chain. The hook set forth herein is preferably resilient throughout its 100

entire length, although I do not wish to be limited to this feature, and the lower end of the latch is bent substantially horizontally as at 32 to extend through a slot 33 formed in the bracket by punching outwardly a lip 34. This lip is positioned to be engaged by the plunger 21 should the clutch move downwardly while the tube frame is held improperly so as to be unable to move toward the fabric. The extreme left end of the latch is bent downwardly as at 35 and extends into a notch 36 punched in the lower arm 14 of the bracket. Said notch defines a shoulder 37 against which the bent end 35 normally is held.

Under normal operations the parts are in the full line position shown in Fig. 1, the substantially horizontal portion 32 of the latch engaging the bracket at 38 at the upper end of the slot 33 and with the hook 31 normally held against the tongue 17. The latch in its normal form has the upright portion 39 thereof disposed at a somewhat larger angle with respect to the portion 32 than is shown in full lines in Fig. 1 so that when the latch is inserted by having the lower end thereof passed into the slot 33 the lower end of the spring latch will be placed under a strain which serves to hold the parts in the position shown in full lines in Fig. 1.

When the tube frame is to be disconnected from the transporting chain the clutch will move inwardly from the full line position shown in Fig. 1 to the left, the stud 20 during this operation engaging the latch and moving the same from the full to the dotted line position in Fig. 1 where the hook 31 will be out of vertical alignment of any part of the transporting chain. This motion on the part of the substantially vertical section of the latch is accompanied also by a slight deformation in the horizontal portion 32, the latter assuming the position indicated in dotted lines in Fig. 1. It will therefore be seen that the portion of the latch which extends into the tube frame is deflected by the clutch and the strain imposed upon the latch is distributed over a greater length of the latch than is true with the usual form of latch. It will be noted in this connection that practically the entire length of the horizontal section 32 lies normally above the lower arm 14 so that said horizontal portion of the latch is capable of considerable downward deflection.

When it is desired to remove the latch a tool such for instance as the screw driver designated at T in Fig. 3 may be inserted in the slot 33 and moved so as to lift the left end of the section 32 of the latch until the hook 35 is entirely clear of the shoulder 37, after which the latch can be withdrawn from the tube frame. It is understood of course that under normal conditions the small hook 35 by its engagement with the shoulder 37 is

effective in retaining the latch in its proper position.

From the foregoing it will be seen that I have provided a simple form of latch the lower portion at least of which is inherently resilient and so formed as to act by its own resilience to be held in position on the tube frame bracket. While I have shown the shoulder 37 as being formed on one side of the slot 33 yet I do not wish to be limited to this particular form of shoulder. It will also be seen that the parts are so related that during the normal operation of the clutch that portion of the latch which extends within the tube frame is capable of deflection so that the strains incident to the flexing of the latch are distributed over a greater length of the latter than usual. Furthermore, it will be noted that the slot 33 which is the opening through which the horizontal portion of the latch extends is formed by punching out the lip 34 to cooperate with the plunger 21 and is also sufficiently large to receive a tool by means of which the latch may be removed from the bracket.

Having thus described my invention it will be seen that changes and modifications may be made therein by those skilled in the art without departing from the spirit and scope of the invention and I do not wish to be limited to the details herein disclosed, but what I claim is:

1. In an Axminster tube frame having a hollow metallic bar, a chain engaging bracket secured to the bar, a resilient chain engaging latch having a portion thereof to engage a part of the chain engaging bracket at the upper end thereof, said bracket having an opening therein, a shoulder on the bracket spaced from the opening, the chain engaging latch having a portion extending through the opening into the hollow bar and having a part extending transversely of the bar and in engagement with the shoulder to prevent movement of the latch portion parallel to the bar out of the hollow bar, said latch portion projecting into the bar being held in engagement with the shoulder by the resilience of the latch.

2. In an Axminster tube frame having a hollow metallic bar, a chain engaging bracket secured to the bar and having an opening therein, a resilient chain engaging latch having a vertical portion to engage the upper part of the bracket and having a lower portion bent to extend through the opening of the bracket to project into the hollow bar, said portion having a part extending transversely of the bar, and means located within the bar and normally fixed with respect thereto to engage the transversely extending part of the horizontal portion of the latch to prevent movement thereof out of the bar in a direction parallel to the bar, said means and lower latch portion being held in cooperative rela-

tionship with each other by the resilience of the latch.

3. In an Axminster tube frame having a hollow metallic bar, a chain engaging bracket secured to the bar and having an arm extending into and secured to the bar, a shoulder on said bracket located within the bar, the bracket having an opening spaced from the shoulder, and a chain engaging resilient latch member substantially L-shaped having a vertical portion to engage the upper part of the bracket and having a lower substantially horizontal portion to extend through the opening in the bracket, the inner end of the horizontal portion being formed with a hook bent to extend transversely of the bar, to engage the shoulder, said shoulder preventing movement of the horizontal extension out of the bar in a direction parallel to the bar, the hook and shoulder being held in cooperative relationship normally by the resilience of the latch.

4. In a tube frame having a hollow metallic bar, a bracket secured to the bar and having a portion extending into and secured thereto, a shoulder on the bracket located within the bar, the bracket having an opening spaced from the shoulder, and a resilient latch engaging said bracket at three spaced points, a hook formed on each end of the latch, one of said points being the upper hook adjacent the upper end of the chain engaging bracket, the second point being at one side of the slot, and the third point being the lower hook engaging the shoulder, said points acting to hold the latch normally in a stressed condition so that the resilience of said latch maintains holding relation between the shoulder and the latch, to prevent the latter from moving out of the bar in a direction parallel to the bar.

5. In a tube frame having a hollow metallic bar, a bracket secured to the bar and having an arm extending into said bar, a pair of surfaces on the bracket each transverse of the bar, said bracket having an opening between the surfaces, and a resilient latch member having a hook at each end thereof, the upper hook to engage and being normally movable with respect to one surface of the chain engaging bracket, and the lower hook being held normally by the resilience of the latch in holding relation with respect to the other surface, the bracket engaging a part of the latch intermediate the hooks and adjacent the slot to create normally a stress in said latch, each hook engaging one of said surfaces of the bracket to prevent movement of the latch out of the bar in a direction parallel to the bar.

6. In a tube frame having a hollow metallic bar, a bracket member secured to the bar and having a substantially vertical chain engaging portion and having a substantially horizontal arm to extend into and be secured

to the bar, and a resilient latch element having substantially vertical and horizontal portions, said latch extending through the bracket member and having the vertical portion thereof engaging the chain engaging portion of the member and having the horizontal portion thereof engaging the arm, said latch being normally held under a strain by reason of its contact with the member, and means having engaging surfaces transverse of the bar to define a holding engagement between the horizontal portions of the member and latch to prevent movement of the latter out of the bar.

7. In a tube frame having a hollow metallic bar, a substantially L-shaped bracket member having a horizontal arm extending into and secured to the bar and having a vertical portion arranged to engage a chain, and a substantially L-shaped resilient latch element passing through the member and engaging the latter at three spaced points, namely, the vertical portion of the latch engaging the upper end of the chain engaging part of the member, the inner end of the horizontal portion of the element having a part extending transversely of the bar and having holding engagement with the arm to prevent movement of the horizontal latch portion out of the bar in a direction parallel to the bar, and the third point of contact being between the member and the element and lying intermediate the other two points, said latch being normally stressed so as to maintain the holding connection between the horizontal portions of the member and element.

8. In a tube frame having a hollow metallic bar, a bracket member having a substantially vertical chain engaging portion and a horizontal arm extending into and secured to the bar, the vertical portion having an opening therethrough, a shoulder carried by the horizontal portion and having a surface transverse of the bar, and an inherently resilient latch element engaging the chain engaging portion of the member adjacent the upper end of the latter and having a substantially horizontal portion to extend through the opening in the member and have holding engagement with the shoulder, that portion of the member above the slot engaging the latch to normally stress said latch to preserve the engagement between the shoulder and said latch, that portion of the latch adjacent the slot having a hook extending transversely of the bar to engage the shoulder and being spaced from the horizontal arm to permit the insertion between said arm and the latch of a tool to disengage said latch from said shoulder, by a motion transverse of the bar.

In testimony whereof I have hereunto affixed my signature.

GEORGE P. FINDLAY.
